(57) **CLAIM**

The ornamental design for a connectivity platform, as shown and described.

DESCRIPTION

FIG. 1 is a front perspective view of a connectivity platform, showing our new design;

FIG. 2 is a top perspective view thereof;

FIG. 3 is a rear perspective view thereof;

FIG. 4 is a right bottom perspective view; and,

FIG. 5 is a front perspective view thereof.

The broken lines in FIGS. 1-4 illustrate unclaimed portions of the connectivity platform and form no part of the claimed design. The broken line showing of the analyzer in FIG. 5 illustrates the unclaimed environment of the claimed design and forms no part thereof.

1 Claim, 5 Drawing Sheets

FIG. 1

FIG. 2

FIG. 3

FIG. 4

FIG. 5
